United States Patent Office.

E. M. POTTER, OF KALAMAZOO, MICHIGAN.

Letters Patent No. 73,197, dated January 7, 1868.

IMPROVEMENT IN CLEVIS.

The Schedule referred to in these Letters Patent and making part of the same.

TO ALL WHOM IT MAY CONCERN:

Be it known that I, E. M. POTTER, of Kalamazoo, in the county of Kalamazoo, and State of Michigan, have invented a new and improved Three-Horse Clevis; and I do hereby declare that the following is a full, clear, and exact description thereof, which will enable others skilled in the art to make and use the same, reference being had to the accompanying drawings, forming a part of this specification, in which—

Figure 1 is a side view of my improved clevis.

Figure 2 is a plan view of the same, with the whiffle-trees shown attached.

Similar letters of reference indicate corresponding parts.

This invention relates to a clevis for the purpose of working more advantageously three horses abreast, when ploughing or performing equivalent work. It consists of two grooved pulleys cast in one piece, and of different diameters, and on which pulleys the whiffle-tree chains work in contrary directions, whereby a compensating action is instituted for the purpose of obviating certain disadvantages which have heretofore attended the working of three horses abreast, as will be hereinafter more fully set forth.

In the drawings, A and A' are the pulleys, of cast or malleable iron, working on a bolt E, which latter passes through the guard B and clevis C, as shown, and is secured in place by a nut and head, in the usual way. The guard B is not shown in fig. 2, for the purpose of giving a better view of the other parts. The object of this guard is to prevent the chains D and D' from getting off the pulleys.

This clevis is attached to the plough in the usual manner, and to the chains are attached the whiffle-trees, in the manner shown. The chain D' is for sustaining the draught of the two outside horses, and the diameter of its pulley is equal to one-half the diameter of the pulley A, on which is attached the chain sustaining the draught of the middle horse. The two whiffle-trees S' are attached to a double-tree W, and is long enough to allow space for the middle horse, as shown. The chains pass more than half around the pulleys, and are firmly secured in the grooves of the same by screws m and m', or other suitable means. By means of these pulleys, of different diameters, there is an equilibrium established between the two outside horses and the middle horse, so that the excess of the working energy of the middle horse, or of the two outside horses, or of either one of the outside horses, is distributed upon the others, which are thus made to sustain their proportionate draught-strain by the turning of the pulleys, and consequent partial winding and unwinding of the chains, according to the excess of draught-force on either chain.

When horses would not work together evenly, as ordinarily attached to a plough, this clevis provides a compensating action, which accomplishes the equality of draught desired. Should any one of the horses slip or stumble, the tension upon the slipping horse is maintained, and the disturbance of the plough thereby prevented.

I am aware that a vertical lever, having arms of different lengths, has been employed for accomplishing a somewhat similar result, (see patent granted to Messrs. Austin & Co.) This device succeeds only where the horses draw evenly, for the vibration of the lever in practice permits but a short and inadequate distance of compensating motion to the chain, and, at the extent of its vibration, is stopped suddenly, thereby occasioning a jar or strain upon the horses. Again, the departure of the lever from a vertical position, maintains the relative difference of leverage throughout the extent of its vibration, so that it requires as much force to be exerted to bring the lever to its vertical position, and thereby restore the chains and whiffle-trees to their proper positions when the outside horses or the middle horse has drawn ahead or fallen back to the extent of the vibration of the lever. These disadvantages, which attend the use of the lever-device, are obviated by my improvement, for, in the first case, the pulleys will, by revolving, permit the maximum extension of either chain, and, in the second case, as the unwinding chain brings its point of attachment, m or m', to coincide with its line of draught and the centre of the bolt, thus destroying the leverage of the extended chain, and allowing the horse or horses attached to the shortened or wound chain to regain their proper position with less effort. This last-described feature is one that has an important relation to the perfect working of the team.

It is well known that in ploughing, the shape of the mould-board often creates a tendency in the plough to bear too much "to land," as it is termed; that is, to actuate the plough to cut deeper into the unploughed portion of the soil, thereby creating side-draught, and causing more or less difficulty for the ploughman, all of which is objectionable. This disadvantage is obviated by my improvements, for the small pulley A' can be placed so as

to come upon the unploughed-side, by simply attaching the clevis to the plough, with reference to the manner in which the field is to be ploughed. The line of draught upon the small pulley is then brought to the right or left of the centre line of the plough, thereby compensating for the action of the mould-boards, before mentioned, and causing the plough to run evenly. It is cheap and durable, and supplies a want long felt.

Having thus described my invention, what I claim as new, and desire to secure by Letters Patent, is—

The employment of the two pulleys A and A', substantially as shown and described, in combination with the ropes or chains D and D', and the clevis-iron C, or other equivalent device for the purpose of working three horses abreast in ploughing or other equivalent operation, all as set forth.

The above specification of my invention signed by me, this 9th day of November, 1867.

E. M. POTTER.
